UNITED STATES PATENT OFFICE.

LEON CHERUBINI, OF HAZLETON, PENNSYLVANIA.

CURTAIN ROD AND SHADE ROLLER SUPPORT.

Application filed July 17, 1925. Serial No. 44,304.

This invention relates to a curtain and shade roller support and one object of the invention is to provide a device of this character which may be conveniently adjusted 5 to fit window frames of varying widths and which will be very firmly held in place when mounted.

Another object of the invention is to so construct the device that the window frame 10 engaging plates may be drawn into tight engagement with the window frame by means of a spring which extends between and is secured to the plates.

Another object of the invention is to provide 15 a device of this character in which the window frame engaging plates will be joined by a connecting bar formed of telescoping sections permitting it to be extended and contracted while the attaching plates 20 are being mounted upon the window frame.

Another object of the invention is to so construct the attaching plates that extensible curtain supporting rods of a conventional construction may be readily supported 25 from the plates and to further so construct the plates that shade roller supporting brackets may be connected therewith and adjusted longitudinally of the plates so that shade rollers of varying lengths 30 may be supported without it being necessary to remove the plates and adjust them upon the window frame.

This invention is illustrated in the accompanying drawings, wherein—

35 Figure 1 is a view in front elevation showing the improved curtain and shade roller support mounted upon a window frame;

Fig. 2 is a longitudinal sectional view taken on the line 2—2 of Fig. 1;

40 Fig. 3 is a fragmentary top plan view showing one side portion of the device;

Fig. 4 is a transverse sectional view taken on the line 4—4 of Fig. 1;

45 Fig. 5 is a view showing the device in rear elevation with portions of the attaching brackets broken off;

Fig. 6 is a transverse sectional view taken on the line 6—6 of Fig. 5;

Fig. 7 is a similar view taken on the line 50 7—7 of Fig. 5;

Fig. 8 is a perspective view of a form of attaching plate to be used in a bay-window, and

55 Fig. 9 is a perspective view of a modified form of attaching plate.

Referring to the accompanying drawings,

the numerals 1 and 2 indicate the attaching plates which are intended to be mounted adjacent the upper end of the window frame 3 at opposite sides thereof. Each plate 60 is formed of sheet metal and has its outer end portion bent to provide a flange 4, from the free edge of which extends prongs 5 adapted to be driven into the window frame or casing, as shown in Fig. 2, and securely 65 anchor the plate to the window frame. The plates taper towards their inner ends, as shown in Fig. 1, and at its inner end each terminates in a tongue extension 6 having 70 side flanges 7 which are folded towards each other into overlying relation to the tongue extension. In order to brace the plates, there has been provided a connecting bar 8 which is formed of telescoping sections 9 and 10, the section 10 sliding into the section 9. These sections 9 and 10 are provided with inturned side flanges 11 and 12 which serve to strengthen the two sections and also serve to prevent the sections from 75 moving transversely out of engagement with each other. The outer end portions of the bar sections fit onto the tongue extensions 6 of the two plates 1 and 2, and these two tongue sections are connected by a spring 13 which extends longitudinally of the connecting bar between the flanges of the two sections, as shown in Fig. 5. The ends of the resilient strand from which the spring is formed are bent to provide eyes 14 to receive fastener tongues 15 struck from the 80 extensions 6 of the plates 1 and 2. The spring is extended longitudinally in order to engage the eyes 14 with the tongues 15 and exert a pulling action which retains the plates 1 and 2 in engagement with the bar sections but permits them to be disconnected. By this arrangement the device can be originally packed with the plates 1 and 2 out of engagement with the sections of the connection bar and, therefore, the spring will 85 not be held in an extended condition except when actually in use. When the device is to be mounted upon a window frame, the eyes of the spring are engaged with the tongues 15 and drawn away from the plate 2 a sufficient distance to permit the tongue extensions of the plates to be fitted into the end portion of the sections 9 and 10 of the connecting bar. The two sections of the connecting bar can then be moved longitudinally of each other in a separating direction until the plates have been moved 90

95

100

105

110

away from each other a sufficient distance to permit the flanges 4 to engage the outer side edges of the window frame. The spring will tend to contract and draw the 5 plates and sections of the connecting bar towards each other so that the flanges will have gripping engagement with the window frame and the teeth or spurs 5 caused to bite into the window frame. If the teeth 10 do not readily penetrate the window frame, the flanges may be struck with a hammer or other pounding implement so that the teeth will be driven into the window frame and firmly anchor the plates.

15 The rods 18 and 19 upon which lace curtains and overdraperies are to be hung are of a conventional construction and each is formed of telescoping sections which have their outer end portions bent to provide arms 20 and 21 provided with vertically disposed openings to receive the upstanding free end portions of the rod supporting pins 22 carried by the plates, as shown in Fig. 4. Adjacent its lower end each of the attaching plates is cut to provide longitudinally extending tongues 23 which are bent back in overhanging relation to the outer faces of the plates and provide tracks adapted to be engaged by the flanges 24 provided upon the base portions 25 of the shade roller engaging brackets 26. By having the brackets 26 mounted upon these tracks, it is possible to shift the brackets longitudinally of the plates so that they may be spaced 30 from each other the proper distance for engagement with the pintles at the ends of a roller of a given length. It will, therefore, be seen that, if a roller already in use is removed and a new one put in place, the 35 bracket can be adjusted to the proper size if the new roller is not of the same length as the roller removed.

40 In Fig. 8, there has been shown a combination attaching plate. This form of plate is for use at a bay window and would be disposed at the points where the sides of the middle window meet the forward side portions of the side windows. This plate which is indicated in 45 general by the numeral 27 is formed of sheet metal and is bent intermediate its length to provide end portions 28 which extend from each other at an angle which will cause them to be properly disposed when 50 the plate is mounted. Openings 29 are provided to receive fastener nails which will be used to secure the plate upon the window frame as this form of attaching plate will not be provided with a toothed flange. In 55 other respects the end portions of the plate 27 are very similar to the plates 1 and 2. The outer ends are tapered to provide tongue extensions 30 and 31 which carry in-turned side flanges or wings 32 and the lower portions of the plate have been cut and

bent to provide tracks 33 which correspond to the tracks 23. There has also been provided pins 34 which are riveted in the plate above the tracks 33 and serve to engage the end portions of the curtain rods.

70 In Fig. 9 there has been shown a further modification and referring to this figure it will be seen that the plate 35 is of a very simplified construction. This plate is for use upon window frames which are not provided with side edges extending from the wall and instead of being provided with a toothed flange has been provided with openings 36 so that fastener nails or screws can be passed through these openings into the window frame. It should be further noted that the tapered end portion which terminates in the flanged tongue extension has been omitted as it is not intended to make use of the spring and connecting bar when this form of plate is used. The plate has, however, been provided with the tracks 37 which correspond to the tracks 23 and 33 and with pins 38 which correspond to the pins 22 and 34.

90 Having thus described the invention, I claim:—

1. In a device of the character described, a mounting bracket comprising a body portion having support-engaging means at its outer end and a tongue extension at its inner end to fit into an end portion of a bar connecting the bracket with a companion bracket, flanges along the upper and lower edges of said tongue extending towards each other in overlying and spaced relation to said tongue to effect snug fit of the tongue into the bar, and a prong extending longitudinally of said tongue between the tongue and inner faces of said flanges with its free end facing said body portion and adapted for hooking engagement with a spring extending longitudinally of the bar between companion mounting brackets.

110 2. A mounting bracket comprising a body portion adapted to be anchored to a support and having a tongue extension at one end, upper and lower flanges carried by said tongue and extending towards each other in spaced overlying relation to the tongue, and a prong extending longitudinally of said tongue between the tongue and flanges with its free end facing said body portion and the flanges serving as guards for the prong.

115 3. A mounting bracket comprising a body portion adapted to be anchored to a support and having a tongue extension at one end, upper and lower flanges carried by said tongue and extending towards each other in spaced overlying relation to the tongue, and a prong struck from said tongue and extending between the tongue and flanges with the flanges serving as guards for the prong.

120 4. In a device of the character described, an attaching plate adapted to be secured up-

on a window frame, said plate provided with a longitudinally extending opening having tongues along its upper and lower edges, said tongues bent outwardly and away from each other to provide flanges overhanging unbroken portions of the plate above and below the opening, and an article-supporting bracket provided with a base portion having underlying flanges adapted to fit beneath said flanges and slidably mount the bracket for movement longitudinally of the attaching plate.

5. In a device of the character described,

an attaching plate adapted to be secured upon a window frame and having an intermediate portion cut to provide a longitudinally extending opening, and tongues at the upper and lower edges of the opening, said tongues being bent outwardly and away from the opening in overhanging relation to the outer face of the plate to provide tracks adapted to engage an article-supporting bracket and mount the bracket for adjustment longitudinally of the plate.

10 In testimony whereof I affix my signature.
LEON CHERUBINI. [L.S.]
